SAND HOSE VALVE OPERABLE TO OPEN AUTOMATICALLY
WHEN CONNECTED TO SANDBOX

Filed May 16, 1947

UNITED STATES PATENT OFFICE

2,566,248

SAND HOSE VALVE OPERABLE TO OPEN AUTOMATICALLY WHEN CONNECTED TO SANDBOX

Max W. Powell, Winnetka, Ill., assignor to Ogle Construction Co., Chicago, Ill.

Application May 16, 1947, Serial No. 748,464

11 Claims. (Cl. 226—127)

1

The invention relates to improvements in sanding hose and nozzles primarily intended for use in sanding diesel locomotives. More particularly, the invention relates to a sanding hose provided with a valved nozzle which is adapted to automatically open to supply sand when the nozzle is placed in the opening in the wall of a sand box on a locomotive and is adapted to automatically close as soon as the nozzle is removed from the sand box, thus avoiding wastage and loss of sand.

Another feature of the invention resides in the use of a sealing plate in connection with the sanding hose which is adapted to seal the opening in the sand box when the hose is positioned therein.

Another feature of the invention resides in the provision of means for supporting the flexible hose pipe in such a manner as to prevent sag of the pipe below a slope which insures a satisfactory flow of sand.

Another feature resides in the improved gate valve mechanism associated with the sanding nozzle.

While the present device has been particularly designed for use in connection with sanding hose and nozzles intended for servicing locomotives, it will be understood that the invention is of wide application and in its broadest aspect is not confined to this particular use.

The invention will be more readily understood by reference to the accompanying drawings and the following detailed description, in which is set forth by way of illustration a specific embodiment of the invention.

Fig. 1 is a view in elevation with parts in section of the sanding apparatus, dotted lines showing different positions of the hose and nozzle, and a portion of a locomotive wheel upon a track being diagrammatically shown also in dotted lines;

Fig. 2 is a detail section on line 2—2 of Fig. 1 but on a larger scale showing the rotatable attachment of the hose and the sand supply pipe;

Fig. 3 is a sectional view on a larger scale than Fig. 1 of the nozzle applied to a sand box opening, the nozzle valve being shown in open position;

Fig. 4 is a front view of the nozzle showing the sealing plate in full lines and the slide plate in dotted lines;

Fig. 5 is a section on line 5—5 of Fig. 3; and

Fig. 6 is a view similar to Fig. 3 with parts in elevation but showing the nozzle removed from the sand box opening and the valve closed.

2

Referring to the drawings, A represents a flexible hose pipe for supplying sand to the sand box of a locomotive. The pipe may be of any suitable material and, as shown, is connected at its upper end by a swivel joint B to a sand supply pipe C supported on an upright post D. By reason of the swivel connection B a single hose pipe may be used to service locomotives standing on two adjacent tracks.

Adjustably carried by the upright D is a clamp E to which is connected one end of a hose supporting rod F provided with a clamp G at its other end adapted to slidably engage the hose A intermediate its ends. As Fig. 1 indicates, the supporting rod F will support the hose when in use at such an angle that sag is eliminated and free flow of sand to the sanding box is insured.

At the lower end of the hose A there is provided a two-part valved nozzle H, which is the subject of the present invention, and which is adapted to be inserted within an opening in a locomotive sand box diagrammatically indicated at I. The nozzle is of such construction that as soon as its end is inserted in the sand box opening and rests upon the portion of the sand box wall beneath the opening, the nozzle valve will be automatically opened to at once supply sand to the sand box, but as soon as the nozzle is removed from the opening the valve will be automatically closed, thereby preventing wastage of sand. Suitable sealing means may be provided in connection with the nozzle so that a tight fit may be insured between the sand box opening and the nozzle.

As shown, the nozzle H consists of two tubular parts 10 and 11, with automatically operating valve means connecting the two parts. The upper part 10 is connected to the hose pipe A by means of a suitable clamp 12. The lower part 11 is adapted to be inserted in the opening in the sand box I with its under surface resting on the portion of the sand box wall beneath the opening.

As shown, the lower nozzle member 11 is provided with a sealing plate 13 which may be secured to the member 11 by any suitable means, as by welding or brazing, at 14. The plane of the sealing plate 13 is preferably at an oblique angle to the central axis of the nozzle portion 11 to which it is secured, and the plate 13 is provided with an opening 15 in alignment with the bore of the nozzle member 11. Thus, the plate 13 serves to seal the opening in the sand box when the nozzle member is inserted therein, and also provides a limiting stop for the nozzle. It will

be apparent that the sealing action is aided by the diagonal mounting of the sealing plate. If a tight joint is desired suitable packing means may be provided at the surface of the sealing plate. Such packing means would render the nozzle fluid tight so that it could be used for supplying liquid as well as fluent materials such as sand and the like, for which it is primarily designed.

The sealing plate 13, together with its opening 15, comprises one member of the automatic valve with which the nozzle H is equipped, the other member comprising a slide plate 16 carried by the upper nozzle member 10 and slidably connected to the sealing plate 13 by any suitable means. As shown, the plates 13 and 16 are maintained in abutting sliding relation by means of guide flanges 17 carried by the sealing plate 13. Upward movement of the slide plate 16 with reference to the sealing plate 13 is limited by a top flange 18 on the sealing plate 13, and similarly, downward movement of the slide plate is limited by a pair of stops or screws 19, 19 carried by the sealing plate. The slide plate 16 is provided with an opening 20 which permits passage from the upper portion of the nozzle into the lower portion thereof of when the openings 20 and 15 in the plates 16 and 13, respectively, are brought into registry. In accordance with my invention this occurs when the lower nozzle member 11 is inserted through the opening in the sand box and rests upon the wall portion or ledge below said opening, the weight of the upper nozzle member 10 and the parts rigid therewith causing the slide member 16 to move by gravity to its lowest position limited by the stops 19. The sand may then be allowed to flow through the nozzle without fear of overflow, as when the box is full the sand will pile up in front of the nozzle opening and prevent further flow, thus providing an automatic cut-off which requires no attention from the operator.

When the nozzle H is removed from the opening on the sand box the weight of the outlet nozzle member 11 and the sealing plate 13 connected thereto causes the sealing plate to move downwardly with reference to the slide plate until the upper end of the slide plate contacts the flange 18 at the upper edge of the sealing plate, in which position the openings 15 and 20 are out of registry and further flow of sand through the nozzle H is automatically cut off.

If desired a pivoted, automatically operating member 25 may be provided to latch the valve in both open and closed position, the latch being held in lock by gravity. It will be seen from the drawings showing the openings in open position (Figs. 3 and 4) that due to the design of these openings when the outlet member 11 slides downward relative to the inlet member 10 to close the opening a minimum of sand grit can be drawn into the contacting faces near the lower half of the opening and none in the upper half, and when said outlet member slides upward relative to the inlet member to open this opening a minimum of sand grit can be drawn into the contacting faces near either the lower or upper half of the opening due in part to the design and in part to the continued outflow in the outlet end until closure is complete.

From the above description the desirability of a vertical sliding movement of the two valve members with reference to each other will be apparent, the outlet member 11 moving upward to open the valve, and downward to close the valve.

The invention has been described in detail for

the purpose of illustration, but it will be obvious that numerous modifications and variations may be resorted to without departing from the spirit of the invention.

5 I claim:

1. In combination with a locomotive sand box having an opening in a wall thereof, and a sanding hose adapted to be connected to a suitable source of supply, a nozzle having valve means for automatically permitting flow of sand to the sand box when the nozzle is supported in the sand box opening, and for automatically cutting off the sand supply when the nozzle is removed from the sand box opening, said nozzle comprising two relatively slidable members interconnected in a plane intersecting the axes of the nozzle members at an oblique angle, and said valve means comprising two relatively slidable plates carried by the nozzle members having openings therein adapted to be brought into or out of registry according as the nozzle is supported in the sand box opening or removed therefrom.
2. In combination with a receptacle to be supplied with fluent material and a flexible hose adapted to be connected to an overhead source of supply, means comprising a two-part valved nozzle connected to the lower end of said hose for automatically supplying fluent material to said receptacle when the nozzle is supported upon a wall portion of the receptacle and for automatically cutting off the supply of fluent material when the nozzle is removed therefrom, said nozzle comprising a pair of relatively slidable tubular members each including a portion of an automatic cutoff valve, one nozzle member having a limiting stop thereon for engagement with a fixed portion of the wall of the receptacle to restrain such member from further downward movement while permitting the other member to slide relative thereto and bring the respective valve portions to the position which opens the valve and permits discharge of fluent material into the receptacle.
3. In combination with a locomotive sand box or the like having an opening in the wall thereof and a sanding hose adapted to be connected to a suitable source of supply located above the opening in the sand box, a nozzle for said hose including gravity actuated valve means for automatically permitting flow of sand to the sand box when the nozzle is supported in the opening and for automatically cutting off the supply of sand when the nozzle is removed from the sand box opening, said nozzle comprising two relatively slidable tubular members each including a part of the valve means, and stop means associated with one of the tubular members for engaging a portion of the sand box wall as the lower end of the nozzle is inserted into the opening to restrain said tubular member while permitting the other nozzle member with its associated valve portion to slide relative to the first tubular member to bring the respective valve portions to the position which opens the valve and permits discharge of sand into the locomotive sand box.
4. In combination with a receptacle to be supplied with fluent material and having an inlet opening in a wall portion thereof and a flexible supply pipe leading from an upper source adapted to supply fluent material by gravity flow into said receptacle through said opening, means comprising a two-part valved nozzle at the lower end of the supply pipe for automatically supplying fluent material to said receptacle when the nozzle is supported in said opening, and for auto-

matically cutting off the supply of fluent material when the nozzle is removed from the opening, said nozzle including relatively slidable inlet and outlet tubular members each having a valve portion connected thereto and movable therewith, one of said tubular members having a sealing plate integral therewith adapted to seal the opening when the nozzle is inserted in the opening and to serve as a stop to restrain further downward movement of the nozzle member to which it is attached while permitting the other nozzle member to slide relative thereto to bring the respective valve portions to the position which opens the valve and permits the flow of sand into the receptacle.

5. In combination with a locomotive sand box or the like having a wall portion and a flexible hose adapted to be connected at its upper end to a suitable source of supply, means comprising a two-part valved nozzle connected to the hose for automatically permitting gravity flow of fluent material to the sand box when the nozzle is supported by said wall portion, and for automatically cutting off the sand supply when the nozzle is removed from the wall portion, said nozzle comprising two relatively slidable nozzle members each including a valve portion, and stop means carried by one of said nozzle members adapted to engage said wall portion when the nozzle is applied thereto to restrain said nozzle member from further downward movement while permitting the other nozzle member to slide relative thereto and bring the respective valve portions to the position which opens the valve and permits the flow of fluent material into the sand box.

6. In combination with a locomotive sand box having an opening in a wall thereof, and a depending flexible sanding hose adapted to be connected at its upper end to a suitable source of supply and to extend downwardly from said source of supply so that sand may flow by gravity therethrough, means comprising a two-part gravity actuated valved nozzle connected with the lower end of the sand hose for automatically permitting flow of sand to the sand box when the nozzle is supported in the sand box opening, and for automatically cutting off the sand supply when the nozzle is removed from the sand box opening, and means for supporting the hose intermediate its ends to eliminate sag such as would interfere with such gravity flow, said nozzle comprising two relatively slidable nozzle members each including a valve portion, and stop means carried by one of said nozzle members adapted to engage a portion of the wall of the sand box below the opening when the nozzle is inserted therein to retain said nozzle member from further downward movement while permitting the other nozzle member to slide relative thereto and bring the respective valve portions to the position which opens the valve and permits flow of sand into the locomotive sand box.

7. In combination with a receptacle to be supplied with fluent material and a flexible conduit adapted to be connected to an elongated source to supply fluent material by gravity to said receptacle, means including a two-part valved nozzle connected to the lower end of the flexible conduit for automatically supplying fluent material to the receptacle when the end of the nozzle is projected into the receptacle and for automatically cutting off the supply of fluent material when the nozzle is removed from the receptacle, said nozzle comprising two relatively

movable tubular nozzle members slidably connected in a plane intersecting the axes of said nozzle members at an oblique angle thereto, and a pair of complementary slide valve members interposed between said nozzle members, one valve member being connected to one of said nozzle members and the other to the other nozzle member, said valve members having openings therein, one in registry with the central passage through one of said nozzle members, and the other being in registry with the central passage through the other nozzle member, and stop means carried by one of the nozzle members adapted for engagement by a wall portion of said receptacle and serving to restrain said nozzle member from further movement while permitting the other nozzle member to slide with reference thereto to bring the respective valve members to the position which opens the valve and permits fluent material to flow therethrough into the receptacle.

8. In combination with a receptacle for fluent material, a flexible supply pipe leading downwardly thereto from an elevated source, and means including a two-part valved nozzle for automatically supplying fluent material to the receptacle when a portion of the nozzle is in engagement with a wall of the receptacle and for automatically cutting off the supply of fluent material to the receptacle when the nozzle is removed therefrom, said nozzle including one nozzle member adapted to be attached to the supply pipe, a second nozzle member slidable relative to the first nozzle member, and a pair of valve members rigid with the respective nozzle members, said second nozzle member having a stop adapted to contact the receptacle wall to restrain downward movement of said nozzle member to which it is connected, while permitting the other member to slide relative thereto to bring the respective valve members into the position which opens the valve and permits the flow of fluent material.

9. In combination with a receptacle for fluent material having an opening in a wall thereof, a flexible supply pipe leading downwardly thereto from an elevated source, and means including a two-part valved nozzle for automatically supplying fluent material to the receptacle when a portion of the nozzle is inserted in the opening and for automatically cutting off the supply of fluent material to the receptacle when the nozzle is removed therefrom, said nozzle comprising relatively slidable inlet and outlet nozzle members, and a slide valve intersecting the nozzle at an oblique angle to the longitudinal axes of the nozzle members, said valve including a stop member comprising a sealing plate rigid with the outlet nozzle member and adapted for engagement with a wall portion when the nozzle is inserted into the wall opening, and a slide plate rigid with the inlet nozzle member and slidably connected to the sealing plate, said stop member when applied to the wall portion serving to restrain the nozzle member to which it is secured from further downward movement while permitting the other nozzle member to slide relative thereto and bring the respective valve portions to the position which opens the valve and permits flow of fluent material into the receptacle.

10. In combination with a receptacle for fluent material, a flexible supply pipe leading downwardly thereto from an elevated source, and means including a two-part valve nozzle for automatically supplying fluent material to the receptacle when a portion of the nozzle is in engagement with a wall of the receptacle and for

automatically cutting off the supply of fluent material to the receptacle when the nozzle is removed therefrom, said nozzle comprising relatively slideable inlet and outlet nozzle members, and a two-part slide valve intersecting the nozzle at an oblique angle to the longitudinal axes of the nozzle members, said valve including a stop member comprising a sealing plate rigid with the outlet nozzle member adapted for engagement with a portion of the wall of the receptacle to restrain further downward movement of the outlet nozzle member while permitting the other nozzle member to slide relative thereto and bring the respective valve portions to the position which opens the valve and permits the flow of fluent material, said nozzle including a slide plate rigid with the inlet nozzle member and slidably connected to the sealing plate, and means for limiting the relatively sliding movement between said plates. 15

11. A sanding apparatus for servicing locomotives, comprising an upright post arranged between a pair of tracks, a sand supply pipe supported at the upper end of said post, a flexible sanding hose having a swivel connection at its upper end with said supply pipe, and having a valved nozzle at its lower end adapted to supply the sand box of a locomotive on either of said tracks, means for eliminating sag in said substantially upright hose comprising a hose supporting rod having an adjustable grip clamp at its lower end embracing the upright post, and a 25 30

5 second clamp at its upper end embracing said hose pipe intermediate its ends, said nozzle comprising two relatively slideable members each including a valve portion rigid therewith, and stop means carried by one of said nozzle members adapted to engage a portion of the wall of the sand box when the nozzle is inserted therein to retain said nozzle member from further downward movement while permitting the other member to slide relative thereto to bring the respective valve portions to the position which opens the valve and permits the flow of sand. 10
